UNITED STATES PATENT OFFICE.

THOMAS ROBINSON, OF NEW YORK, N. Y.

PREPARED ROOFING.

Application filed June 1, 1925. Serial No. 33,976.

This invention relates to a new roofing product of the type generally referred to in the trade as prepared roofings, and which is composed of various materials of a water-resistant character formed into elements of different kinds appropriate for roofing and general building purposes. More particularly the invention is intended to provide a new product which is cheap, durable, easily laid, and of considerable rigidity, and which, when laid in place, gives the roof an attractive appearance. Also, the invention is intended to provide a product which is made of ingredients available at low prices, and which may be employed in the manufacture of the new product with low labor charges.

Prepared roofings of various kinds are now in wide use and they afford numerous advantages over wooden shingles, tiles of vitreous materials, and other similar roofing elements. These prepared roofings are not only much cheaper than the materials heretofore employed, and may be handled and laid more conveniently, but, in addition, as compared with wooden shingles, they reduce the fire hazard materially. Such prepared products are sold commercially in various forms, such as rolls and as single and multi-unit shingles. That type which has met with the greatest commercial success includes a base of different materials, to the surface of which is customarily applied a coating of a water-resistant product, over which is then placed a coating of a wearing material.

A typical example of such prepared roofing consists of a felt made of wool, rags, or other similar material, suitably felted together and saturated with asphalt. Over one or both surfaces of this base is then applied a layer of asphalt of a melting point such that it will readily withstand solar heat, and on the surface of the element which is to lie uppermost and thus be exposed to the weather, is applied a coating of crushed slate partially embedded in the asphalt layer before the latter has thoroughly hardened.

Such products are satisfactory in many respects although a product which includes a felt base deteriorates with more or less

rapidity upon exposure to the weather, due to the rotting of the felt. When these elements take the form of shingles which are laid in courses in the usual manner, having an exposed margin, the rotting of the felt causes the exposed edges to warp and curl and the roof becomes unsightly and may also have openings through which leakage takes place. Another objection to such products lies in the fact that they are nearly always of uniform thickness from one end to the other, and thus the exposed margins are comparatively thin. The appearance of the roof is much more slight when the roofing elements covering it have a thickened butt, but such elements cannot be readily made with a felt base. Another major objection is that the products ordinarily used in making the base, such as felt, asbestos board, and the like, are quite expensive, so that the cost of these elements, while less than wood, is quite a substantial item in building construction.

The object of the present invention is to provide a new roofing product which may be manufactured at a lower cost than prepared roofings now in use, and in any of the shapes and forms desirable for building purposes. More specifically, the present invention involves the provision of a product which includes a body member made up of comminuted inert material and a cementitious binder which is enclosed in a jacket of a water-proof sheeted material. In one form of the invention this jacket is doubled or folded upon itself in such a way as to provide a guide which is useful in laying the elements in overlapping courses, and the doubled portion of the jacket serves not only to strengthen the element and render it more rigid, but also to give it added thickness at a point such that the elements of the course next above will appear to have a butt of somewhat greater thickness than is actually the case. The new product is composed throughout of materials which do not deteriorate upon exposure to the weather and may readily be made in the tapered form, which is most suitable for roofing purposes. In certain features the new element resembles the roofing product disclosed in my copending application filed April 10,

1925, Ser. No. 22,057, but differs therefrom in certain respects which will be made clear as this description proceeds.

For a better understanding of the invention, reference will now be made to the accompanying drawings, in which

Figs. 1, 2, and 3 are face views of multiple and single unit shingles constructed in accordance with the present invention,

10 Fig. 4 is a longitudinal, sectional view of these elements.

Fig. 5 is a longitudinal, sectional view similar to Fig. 4, but showing the element at an intermediate stage in its manufacture,

15 Fig. 6 is a longitudinal, sectional view through the central portion of the element made on an enlarged scale, and

Fig. 7 is a longitudinal, sectional view of a detail of the shingle shown in Fig. 3.

20 Fig. 8 is a sectional view similar to Fig. 7, but showing the relation of the shingles when laid in the ordinary manner in overlapping courses.

Referring now to these drawings, there is illustrated in Fig. 1, a three-unit strip shingle 10 of the ordinary form, which is provided with cut-out portions 11, in its forward edge, which is the edge normally exposed when the elements are laid in courses.

25 30 These cut-out indentations divide this edge of the element into tabs 12 which correspond in appearance to the ends of single unit elements. Thus, when a series of the multi-unit shingles are laid in courses, the cut-out indentations defining the tabs give the roof the same appearance as it would have if covered with single unit shingles laid in spaced relation.

35 In Fig. 2 there is shown a single unit element 13 having cut-out portions 14 along either lateral edge at the forward end. These elements are also laid side by side in courses, with their rear portions 15 of their lateral edges lying in contact while the cut-outs 14 of adjacent shingles give these shingles the appearance of being spaced apart. The shingle 16 in Fig. 3 is the ordinary rectangular unit which is to be laid in courses but with the elements of the course spaced apart in the usual manner.

40 45 The new product may be made in any of the ordinary forms, such, for instance, as those illustrated, and others, and may be made either of uniform or tapering cross section from front to rear, the latter being preferable.

50 55 This element comprises, as shown more clearly in the other figures of the drawings, a jacket sheet 17, which is somewhat more than twice as long as the length of the element. This sheet is folded transversely, as at 18. This jacket may be made of various sheeted materials, of which a water-resistant paper, such as one impregnated with asphalt, is typical. It is preferably, though

not necessarily, water-resistant and should have a fair degree of strength. It serves to confine the body of the new product, and is particularly useful during the course of manufacture for this purpose. Also, it contributes a certain amount of strength and durability to the final product, although the resistance of the new material to water does not depend on this jacket to any considerable extent, nor is the rigidity of the product thus dependent. Accordingly, various materials other than asphalt paper will suggest themselves to those skilled in the art as being useful for the purpose. Such products as asbestos paper or coarse grade ordinary paper not impregnated, may be used also, although asphalt paper is perhaps preferable because it is water-proof and it is of low cost.

60 65 A jacket sheet of the proper dimensions having first been secured, it is folded in the manner described, and then supported in any convenient way, preferably with its sides relieved from strain and spaced apart according to the thickness of the element to be produced. If this element is to be tapered, then the sides of the sheet are supported in diverging relation. In the fold of the sheet thus formed there is now introduced the filler which is made up of a comminuted, inert material, together with a cementitious binding compound. This inert material may be of various kinds, as, for example, crushed slate, crushed petroleum coke, infusorial earth, sand, gravel, pumice stone, ground cork, fibrous products, such as asbestos and peat, and other similar materials of this character. The natural product known as asbestos sand, may also be used. This is a waste product in the manufacture of asbestos which is entirely satisfactory in the manufacture of these elements and may be secured at an extremely low cost. The plastic binding compound employed is preferably a bituminous substance, such as asphalt.

70 75 In the manufacture of the elements the filling material which goes to make up the body enclosed within the jacket sheet is introduced into the sheet while the latter is supported in folded relation. Prior to the introduction of the mass of filler, it is desirable to fold one ply of the sheet upon itself, as at 19. It will be seen from Fig. 6 that this fold involves the formation of a loop, the end of which is designated at 20, this loop being then bent to one side so as to lie against part of the ply 21. The purpose of folding this ply of the sheet upon itself at this point is to give the element an added thickness and the transverse ply is preferably placed so that its forward edge 20 defines the rear end of the normally exposed margin of the element. Also, as is apparent from Fig. 6, this increased thick-

ness of jacket material at this point, being overlain by the forward end of the elements in the course next above when the elements are laid in the usual way, raises the ends 10 of these elements in such a way as to give them the appearance of having a much thicker butt than is actually the case. The raising of the butt ends of the elements is brought out more clearly in Fig. 8, where it 15 will be seen that the elements of one course are laid so that the butts are in substantial registry with the folds of the shingles of the course next beneath, and thus the exposed butts appear to have a greater thickness 20 than is actually the case. Thus the fold at this point serves the purpose not only of giving the element transverse rigidity, of providing a guide for laying the elements of the course next above, but also of raising the exposed ends of these elements so as to give them the appearance of greater thickness. In addition, the added thickness in 25 the jacket at this point assists in preventing water from getting in between the elements. As the water is blown up the roof, and flows over the exposed faces of the elements, if 30 there were no increased thickness at the point 20 the water would be free to flow directly between the face of one element and the under surface of the element above it. By making the element thicker at this point, thus providing a jog, as shown in Fig. 6, the water blown by the wind makes an abrupt change of direction and only part, if 35 any, will flow on beyond the jog.

In making these elements the body mixture is introduced into the fold 18 of the jacket, while the opposite plies of the jacket are held in the desired spaced relation and 40 after the fold 19 has been formed. The mixture which I have found to be highly satisfactory for the purpose is one consisting of asbestos sand and asphalt, the latter having a melting point such that it will 45 withstand solar heat. This mixture is introduced into the jacket in the desired quantity, packed tight by suitable means, and then allowed to harden. If desired, the plies of the jacket may be cut so as to leave 50 portions 22, which extend somewhat beyond the end of the body as shown at 23. Preferably before the body has completely hardened, these ends are turned inwardly so as to overlap, as shown more clearly in Fig. 55 4, so that both ends of the body and both faces are enclosed within the jacket, the lateral edges of the body only being exposed.

After the body has hardened to some extent, the cut-outs 11 and 14 may be formed in the forward edge of the element, and thereafter the entire element is given a surface coating of water-resistant material, such as asphalt. This material covers not only 60 the jacket, the exposed end portions of the

body, but also covers those portions of the body which would normally be exposed in the cut-out indentations. While this surface coating is still in a plastic condition, a wear surface is formed on the upper face of the 70 body, and the body end, by applying a layer of comminuted material, such as crushed slate, indicated at 24. After the waterproof coating has hardened to the desired extent, the elements are ready for storage 75 or transportation.

If desired, the elements may be manufactured in the form of a continuous strip, the different operations being carried on prior to cutting the elements into the smaller 80 units, and in this process the sheet of jacket material is drawn from a supply, folded as desired, filled, the cut-outs formed, and the various other operations carried on while the sheet is in movement. This process is 85 comparatively simple and permits the manufacture of the products at a low cost.

In the element illustrated in Fig. 7, the upper ply 21 of the sheet has been formed with two loops, the under of which is designated 20, and the upper 25. The upper fold of the loop 20 extends rearwardly to the point 26, which is somewhat beyond the point 27, where the first fold in the sheet is made. With this arrangement, there are 90 five plies of the material in the transverse thickened portion, and the sheet gradually tapers in thickness, as illustrated, so that there is no distinct bulge to the rear of the jog which serves as the guide for laying the 100 elements of the course above. If desired, both plies may be of the same width, and may be laid directly one upon another, and also, more than two folds such as are shown in Fig. 7, may be employed. It will be 105 understood that the jacket material is somewhat thinner than as illustrated in Figs. 4 to 7, inclusive, where the thickness of the sheet is somewhat out of proportion in order to make the illustration clearer. Ordinarily the length of the fold in the ply of the sheet from the point 20 to that designated 28 will 110 vary from somewhat less than one inch to three inches, depending on the character of the element to be made, and the manner in 115 which it is laid. The forward edge of the fold indicated at 20, which defines the rear edge of the exposed margin of the element, will also be placed at a point which will be determined by the manner in which the elements are laid. Ordinarily the elements are laid in overlapping courses, so that the rear end of each element is overlapped by the forward ends of the elements in the two next 120 higher courses. Consequently the element has a length which is equal to twice the width of the exposed margin plus a distance designated as the head-lap, which is the amount by which the element is overlapped 125 by the elements in the second higher course. 130

Accordingly, the line of the folding 20 will lie somewhat forward of the transverse median line of the element and in case the element is one having cut-outs as shown in 5 Fig. 1, the line of fold will lie flush with the rear ends of the cut-outs.

In constructing the new product, I prefer to employ asphalt impregnated paper for the jacket and a mixture of asphalt and asbestos sand for the filler. Asbestos sand is a commercial product which consists of fine particles of asbestos substantially without fibre and sometimes includes a little gangue. This product has a somewhat lower specific 15 gravity than asphalt. Consequently, when a mixture of asphalt and this material is introduced into the jacket, then the asbestos sand to a large extent remains suspended so that in the filler, that portion which 20 occupies the fold in the jacket is composed nearly entirely of asphalt, while the portion at the butt will contain most of the asbestos sand. By raising the temperature of the mixture so as to give the asphalt the desired 25 fluidity, the asbestos sand will remain suspended and because of its less specific gravity than the asphalt, will in fact occupy the greater portion at the butt of the shingle. I have found that the rigidity of the element 30 will vary to some extent, according to the density of the materials which form the filler, but when such a mixture is employed, as a filler or body in a tapered element, then the rigidity is not impaired because the 35 heavier material, that is, the asphalt, will occupy the thinner part of the body, while the lighter material, that is, the mixture of asphalt and asbestos sand, will occupy the thicker portion or butt. Since the butt is of 40 increased thickness, and there is a greater quantity of filler present at this point, the fact that the filler is comparatively lighter does not reduce the rigidity of the element in any detrimental way. The desired gradation 45 is effected by regulating the temperature of the mixture of asbestos sand and asphalt, and when the filler cools and sets the particles of asbestos sand remain in fixed position.

50 While I have described the advantages of providing the fold 19 in one ply of the jacket sheet in some detail, in connection with an element in which no metal is used, I contemplate that it may be desirable in 55 some instances to provide the exposed margin of the element, together with the butt end and the edges of the element adjacent this end, with a protective sheathing of metal which will take the form of a shell of 60 appropriate shape applied to this portion of the element and held in place by suitable adhesive material. When such a shell of metal is to be applied to a base material, it is desirable to make some provision for covering the rear edge of the element so that 65

water cannot enter between the metal and the base and thus eventually bring about a separation of the base and the metal. The new element herein described lends itself most satisfactorily to the manufacture of 70 such a metal-clad product, because a pre-formed shell may be applied to the forward face of the element and its rear edge may be inserted between the ply 21 and the fold which terminates at the point 20. For this 75 purpose it will simply be necessary to break the asphalt film along the forward edge of the fold at 20, then separate the two plies a slight distance so that the rear edge of the metal may be inserted between the ply 80 21 and the folded portion, the end of which is designated at 20. Prior to the introduction of the rear edge of the shell, the faces of the plies are coated with asphalt or some similar material of this character, a film of 85 which is also applied over the end of the fold along the line 20. The rear edge of the metal is thus held firmly in place and is entirely protected so that no water can enter between the base and metal from the 90 rear.

I claim:

1. A tapered roofing element comprising the combination of a body of hardened plastic material and a sheet folded over to enclose one end of the body, the two plies of the sheet also covering the opposite faces of the body and one of these plies being folded upon itself to increase the thickness of the 95 ply in a zone extending transversely of the 100 element and spaced from the ends of the latter.

2. A tapered roofing element comprising the combination of a body of comminuted material and a cementitious binder and a 105 sheet folded over one end of the body and covering the opposite faces of the body, one 110 ply of the sheet being folded upon itself to provide a thickened portion extending transversely of the element, the forward edge of 115 the thickened portion being coincident with the rear edge of the normally exposed margin of the element.

3. A tapered roofing element comprising the combination of a body of comminuted material and a cementitious binder, the body 115 having gradually increasing thickness from one end to the other, and a sheet folded over the thin end of the body and covering the opposite faces of the body, one ply of this 120 sheet being folded into a loop which is bent to lie against the surface of the ply, this loop extending transversely of the element and lying spaced from the edges of the latter.

4. A tapered roofing element comprising the combination of a body formed of a hardened plastic material and a sheet folded over to enclose one end of the body, the two plies of the sheet covering the opposite faces of the body and one of these plies being 125 130

olded upon itself to provide a plurality of loops lying one upon another, the lowest loop lying against the face of the ply and the loops above being of successively greater width, these loops providing a band of increased thickness extending transversely of the element and lying spaced from the ends hereof.

5. A tapered roofing element comprising the combination of a body of comminuted material and a cementitious binder, and a sheet folded over to enclose one end of the body, the two plies of the sheet covering the opposite faces of the body and one of these plies being folded upon itself to provide a plurality of loops lying one upon another and parallel with the face of the ply, the forward edges of these loops lying in registry and also lying coincident with the rear edge of the normally exposed margin of the element.

6. A tapered roofing element comprising the combination of a sheet doubled upon itself to provide a fold with the plies of the sheet diverging from the line of fold, and a body lying within the sheet and comprised of asbestos sand and asphalt, the density of the body varying from one end to the other with the denser portions lying nearer the thinner end of the element.

7. A tapered roofing element comprising the combination of a body of hardened plastic material, a sheet folded over to enclose one end of the body, the two plies of the sheet also covering the opposite faces of the body, and one of these plies being folded upon itself to increase the thickness of the ply in a zone extending transversely of the element between the ends of the latter, and a coating of a water-proof substance applied over the sheet and the exposed ends of the element.

8. A tapered roofing element comprising the combination of a body of hardened plastic material, a sheet folded over to enclose one end of the body, the two plies of the sheet also covering the opposite faces of the body and one of these plies being folded upon itself to increase the thickness of the ply in a zone extending transversely of the element between the ends of the latter, a coating of a water-proof substance applied over the sheet and the exposed ends of the

element, and a wear surface applied over the face of the sheet having the transverse fold 55 and also over the end of the element.

9. A tapered roofing element comprising the combination of a body of hardened plastic material and a sheet folded over to enclose one end of the body, the two plies of 60 the sheet also covering the opposite faces of the body and one of these plies being folded upon itself to increase the thickness of the ply in a zone extending transversely of the element between the ends of the latter, and 65 one edge of the element being provided with a plurality of cutout indentations defining tabs.

10. A tapered roofing element comprising the combination of a body of hardened plastic material, a sheet folded over to enclose 70 one end of the body, the two plies of the sheet also covering the opposite faces of the body and one of these plies being folded upon itself to increase the thickness of the 75 ply in a zone extending transversely of the element between the ends of the latter, and one edge of the element being provided with a plurality of cut-out indentations defining tabs, and a coating of water-proof material 80 applied to the sheet and covering those portions of the body which are exposed along either side of the sheet and also in the cut-out indentations.

11. A tapered roofing element comprising 85 the combination of a body of hardened plastic material, a sheet folded over to enclose one end of the body, the two plies of the sheet also covering the opposite faces of the body and one of these plies being folded 90 upon itself to increase the thickness of the ply in a zone extending transversely of the element between the ends of the latter, and one edge of the element being provided with a plurality of cut-out indentations defining 95 tabs, a coating of water-proof material applied to the sheet and covering those portions of the body which are exposed along either side of the sheet and also in the cut-out indentations, and a layer of crushed mineral matter partially embedded in the water-proof coating and covering the end of the element and the face of the folded ply. 100

In testimony whereof I affix my signature.

THOMAS ROBINSON.
